UNITED STATES PATENT OFFICE

JOSEPH HEATON SOUTHERN, OF REDCAR, ENGLAND

FIREPROOF FLOOR

Application filed May 29, 1928, Serial No. 281,541, and in Great Britain August 13, 1927.

This invention relates to fireproof floors and has for its object to provide an improved method of constructing a floor of this type.

The method according to the present invention consists in disposing a plurality of hollow metal beams side by side over the whole area of the floor space, and covering the assembly with concrete to form a unitary structure.

10 The invention will be described by way of example with reference to the accompanying drawings, wherein:—

Fig. 1 is a perspective view of a hollow beam or column complete with the exception of end plates;

Fig. 2 is a similar diagrammatic view of part of a floor:

Figs. 3 and 4 are plan and end elevation detail views respectively of the end plates 20 and joints.

Figs. 5, 6, 7 and 8 are end elevations of modified methods of constructing the hollow beam or column;

Fig. 9 is an end and part sectional elevation of a convenient method and apparatus for pre-casting concrete or the like on to one side of the hollow beam or column; and

Fig. 10 is a corresponding side elevation of the apparatus;

Fig. 11 is an isometric view corresponding to Figs. 9 and 10.

Referring to the drawings:—

The hollow beam or column *a* (Fig. 1) is made of metal in the form of a flanged trough, the aperture of which is closed by a plate *b*, welded, bolted or otherwise secured thereto, so that the whole constitutes a box section beam or column. A plain or corrugated mesh *c* is fixed underneath the plate and serves to support the concrete fire proofing and plaster *d* on the underneath side (Fig. 2). The mesh *c* may be anything suitable such as expanded metal or welded wire fabric.

When the beams *a* are used in the construction of a floor and are placed in position across the end supports, channel sections *e* are formed which are filled in with concrete. It will be seen from Figs. 2 and 4 that the bottom plates *b* project slightly beyond the flanges of the trough, and this arrange-

ment allows the concrete to seal finally the cavity between the flanges.

Plates *f* are welded to the sides of the troughs, near the ends so that concrete can be filled in between the plates and the end of the beam or column to hermetically seal and make the beam or column fire and rust proof, and a topping *g* of concrete is laid on the assembled beams when used in a floor.

If desired, or necessary, the ends of the beams or columns may be cut back as shown by dotted lines *h* *h*, in Fig. 1, to allow of easy filling of concrete.

If concrete be used and the hollow steel beam is not of sufficient strength to carry the full load required for the floor and the like, additional steel may be embedded in the bottom, and or top of the concrete enabling the concrete beams, and the steel beams to carry any designed load by working either 70 separately or in conjunction.

In modifications of the invention the hollow beams or columns may be formed of two Z-section sides *i* *i*, and two flat plates *b*, *j*, as shown in Fig. 5; or may be formed of two flat side plates *k*, *k*, two flat top and bottom plates *j*, *b*, and four angle sections *l*, *l*, *l*, *l*, as shown in Fig. 6; or of a channel section *m*, a flat plate *b*, and two angle sections *l*, *l*, which form the flanges of the beam or column, as shown in Fig. 7; or of two channel sections *n*, *n*, which form the narrower sides of the beam or column, and two flat plates *b*, *j*, as shown in Fig. 8; all welded, bolted or riveted together to form a box section. In some cases the plate *b* may be dispensed with as hereinbefore described. Any other suitable arrangement of plates and various sections may be employed to form a box section beam or column without departing from the scope of the invention.

A convenient method of pre-casting concrete on to the sides of the columns or beams is illustrated in Figs. 9, 10 and 11. Therein, *a* is the beam or column. Steel or other shuttering *t* is arranged around the edges of the beam to the required depth of the concrete covering, and is retained in position by clamps *u* which engage the flanges of the trough. Notches *v* are provided at intervals 100

in the edge of the shuttering *t* to allow the ends of the reinforcing mesh *c* to be passed therethrough and turned over the edges of the trough as shown in Fig. 11. Concrete is then placed on the face of the beam to the level of the shuttering *t*, and allowed to set, when the shuttering *t* and clamps *u* are removed.

By the use of the present invention fire-clay tiles and their supporting members are dispensed with. Further, the troublesome operation known as "centering" becomes unnecessary, resulting in an economy in time in construction.

15 What I claim and desire to secure by Letters Patent is:—

1. A hollow floor comprising a plurality of steel substantially rectangular independent box-like beams closed by end plates at 20 each end disposed in parallel relationship and encased and hermetically sealed on all external surfaces with a concrete heat insulating and rust resisting covering which also forms a continuous floor surface the beams 25 being of such cross section number and disposition as to be capable unaided of carrying substantially the whole of the maximum load which the floor is required to carry.

2. A hollow floor as claimed in claim 1 in 30 which a supplementary hermetic seal to the box-like beams is provided by welding or brazing all seams.

3. A hollow floor as claimed in claim 1 in which the box-like beams are formed by 35 securing a suitable base plate to a beam of inverted trough form such base plate having lateral extensions which in the case of adjacent beams operate as distance pieces and are placed in abutment.

40 4. A hollow floor comprising a plurality of substantially rectangular steel box-like beams closed by end plates at each end disposed in parallel relationship and encased and hermetically sealed on all external surfaces with a concrete heat insulating and rust 45 resisting covering which also forms a continuous floor surface the beams being of such cross section number and disposition as to be capable unaided of carrying at least the 50 dead weight of construction of the completed floor.

5. A floor as claimed in claim 1 in which the effect on the added load carrying capacity of the concrete is small in relation to the 55 load carrying capacity of the beams of the floor.

6. A hollow floor comprising a plurality of steel substantially rectangular independent box-like beams closed by end plates at each 60 end disposed in parallel relationship and encased and hermetically sealed on all external surfaces with a concrete heat insulating and rust resisting covering which also forms a continuous floor surface, the beams being of 65 such cross section, number and disposition as

to be capable unaided of carrying substantially the whole of the maximum load which the floor is required to carry, the box-like beams each comprising a flat horizontal compression member, two vertical shear members and a horizontal tensile member extending beyond the shear members.

7. A hollow floor comprising a plurality of steel substantially rectangular independent box-like beams closed by end plates at each end disposed in parallel relationship and encased and hermetically sealed on all external surfaces with a concrete heat insulating and rust resisting covering which also forms a continuous floor surface, the beams being of such cross section, number and disposition as to be capable unaided of carrying at least the dead weight of construction of the completed floor, the box-like beams each comprising a flat horizontal compression member, two vertical shear members and a horizontal tensile member extending beyond the shear members.

8. In the art of making hollow floors comprising a plurality of steel substantially rectangular independent box-like beams, the step consisting in inverting the beam and pre-casting a layer of concrete on to the surface which is lowermost when the beam is in position.

9. In the art of making hollow floors comprising a plurality of steel substantially rectangular independent box-like beams, the step consisting in inverting the beam, spreading wire mesh over the exposed surface, and pre-casting a layer of concrete on to the surface which is lowermost when the beam is in position.

10. Process of building hollow fireproof, rustproof floors consisting in utilizing metal box-shaped beam members having extending flanges, to support the load, inverting the beams and casting on the base thereof a layer of concrete, placing the beams in parallel relationship with abutting flanges over the area to be covered and hermetically sealing the beams by pouring concrete over the remaining external surfaces thereof.

In testimony whereof, I affix my signature.

JOSEPH HEATON SOUTHERN.
